(57) **CLAIM**

The ornamental design for binoculars, as shown and described.

DESCRIPTION

FIG. 1 is a perspective view of the top, front and right side of binoculars showing my new design;

FIG. 2 is a perspective view of the top, rear, left side and left thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The elements shown in broken lines are for illustrative purposes only and form no part of the claimed design, and the chain line shows a boundary of the portion to be claimed and the portion not to be claimed.

1 Claim, 6 Drawing Sheets
